O. L. KLEBER.
PRINTING TELEGRAPH MECHANISM.
APPLICATION FILED JUNE 8, 1914.

1,145,490.

Patented July 6, 1915.

UNITED STATES PATENT OFFICE.

OSCAR L. KLEBER, OF PITTSBURGH, PENNSYLVANIA.

PRINTING-TELEGRAPH MECHANISM.

1,145,490.

Specification of Letters Patent.

Patented July 6, 1915.

Application filed June 8, 1914. Serial No. 843,744.

To all whom it may concern:

Be it known that I, OSCAR L. KLEBER, residing at Pittsburgh, in the county of Allegheny and State of Pennsylvania, have invented certain new and useful Improvements in Printing-Telegraph Mechanisms, of which the following is a specification.

This invention refers to printing telegraph mechanisms of that class in which is included a rotary type or printing wheel and electromechanical devices for actuating the wheel at the required times, to bring it to the desired printing position, return it to the normal position after the printing operation has been effected, and in which the electric impulses that control and set into action the said electromechanical devices are sent out from the transmission end of the system.

My present invention specifically has reference to improvements in the printing telegraph system disclosed in my copending application No. 616,740, filed March 24, 1913, and especially with reference to the means for causing the type wheel to rotate with the continuously rotating motor actuated shaft, which in my system above referred to is arranged for being set in operation by the operator at the transmitter end of the system when he desires to send in the message. In my aforesaid copending application, the type wheel or wheels are held to turn with the shaft at the desired times by means of a spring disk mounted on and which turns with the shaft, and which is held up against the side of the wheel under pressure by a tension spring.

From practical experience it has developed that the spring pressure against the wheel is of such an extent that it tends to wear the operating gear, etc., besides putting so much pressure on the dot or releasing finger as to necessitate a strong pull of the magnet that coöperates with the said finger to draw it away from the wheel face and its stop portion, requiring, as it were, a strong current for effectively and at proper timing release the said finger. For the same reason, a strong motor is required to turn the type wheel shaft against the frictional resistance applied by the springs.

The primary purpose of my present invention is the provision of an improved means for controlling the rotation of and the connection of the wheel and the shaft that remedies all of the objections noted,

and which materially simplifies the construction of the type wheel controlling mechanism and the type wheel setting and releasing operations rendered the more positive and absolutely certain with respect to the proper setting of the wheel.

Another and important object of my present invention is to provide an improved means for carrying around the type wheel with the shaft in such manner that the continuous heavy friction incident in the use of the means for locking the wheel with the shaft shown in my copending application is not only entirely avoided, but the rotating pull force is doubled and arranged to act only when the type wheel is entirely free from the hold-back action of the arresting or stop finger.

With other objects in view, all of which will be hereinafter explained, my present invention, in its generic nature, comprehends an electromagnet rotatable with the actuating shaft that is so located and held for co-operating with the type wheel that when energized it electrically grips the wheel and causes it to turn with the shaft until the magnet is deenergized, the latter operation in my present construction being entirely under the control of the "dot finger" which in its swinging movements controls a switch which in turn controls the current from the battery or other electric source to the magnet.

In its more subordinate feature, my present invention embodies certain details of construction and novel arrangement of parts, all of which will be hereinafter fully explained, specifically pointed out in the appended claims and illustrated in the accompanying drawings, in which:

Figure 1 is a diagrammatic perspective showing the general arrangement of my improved type wheel control mechanism. Fig. 2 is a diagrammatic plan view showing the shifting switch in its various positions, parts of the complete device being omitted. Fig. 3 is a longitudinal section showing the magnet construction. Fig. 4 is a section on the line 4-4 of Fig. 3.

My improvements, as before stated, have reference to the means for clutching or interlocking the type wheel to cause it to rotate with the rotary shaft on which it is mounted, and in the practical application of my said present improvements to the printing telegraph system or mechanism shown and

described in my copending application, no change is made in the arrangement of the dot, dash and stop fingers and the dot, dash and stop means on the type wheel or the electromechanical devices that operate the stop, dash and dot fingers, the printing elements and the carriage feed devices.

In the drawings, I have only illustrated so much of my printing telegraph system disclosed in my copending application referred to as is necessary to disclose the practical arrangement, the operation of and the advantages of the present improvements.

In carrying out my new invention, I provide the type wheel 4, that is loosely mounted on the continuously rotating or operating shaft 1, when the motive power therefore is on, with a solid metal disk 3, fixedly held on the face of the wheel, and which forms, as it were, the armature for an electromagnet 2, that is mounted upon and is rotatable with the shaft 1. Electromagnet 2, it will be noted, is so set that it will hold by magnetic attraction, when the magnet 2 is energized, the disk 3 on the type wheel.

5 designates a rubber disk or commutator provided with contact plates 51—52 to which connect the wires 53—54 that join the said commutator with the magnet coils 2—2, as shown. Brush or contact springs 8 and 9 are suitably mounted on an arm of the machine framing, from which lead the wires to the source of electric current, which may be a battery 10, as shown, or a lead from the main line.

As in my copending application the stop dot and dash fingers x , y and z coöperate with a rock shaft 7, loosely journaled in bearing boxes on the framing, and to the said shaft the dash finger z is fixedly connected to thereby rock with the shaft to move into and out of engagement with the "stops" side of the type wheel.

The stop and dot fingers x and y have pendent shanks and are hingedly connected at their lower end and a spring x' serves to normally force the finger y inwardly. As in my other case referred to, the fingers x and y seat loosely in recesses 72—72 in the side of shaft 7 and they, when the shaft is rocked in the direction of the arrow (see Fig. 1) in the manner presently explained, engage the face 73 of the shaft 7 which acts as a cam to swing the fingers x and y away from the face of the type wheel, while at the same time the dash finger drops against the face of the said wheel—the dash stop selecting position.

As in my copending application, a primary magnet P. M. in circuit with the main line, controls the aforesaid movement of the several fingers, it being understood that when an impulse is sent from the transmitter through the main line the primary magnet 65 rocks the shaft 7, and pulls the stop finger x

outwardly from the type wheel, thereby releasing the said wheel while the dash finger drops against the said wheel.

12 designates a switch that is so mounted that one end is adapted for engaging the contact 8 in the local or battery circuit 10, and the other end is in position to engage the stop finger y , and in such manner that as the said stop finger y is shifted so is the switch member moved either to or from engagement with the contact 8.

By reason of the peculiar arrangement of the several parts hereinbefore described, and shown in the drawing, it follows that each impulse that is sent in from the transmitter end of the system actuates the shaft 7 and in consequence the dot finger y , and as the finger y is thus pulled back to release the type wheel, the movement of the said finger y shifts switch 12, closes in the local circuit 10, energizes the magnets 2—2 and thereby clutches the type wheel to the rotary or operating shaft, it being understood that the time or length of energy of the magnets 2—2 is dependent on the action of the operator at the sending or transmitting end of the system.

When the operator shifts his transmitting keys and breaks the impulse to the primary magnet that rock the shaft 7, the dot finger y , through the medium of a spring x , is swung back against the face of the type wheel, it being understood that during the aforesaid operation the magnets 2—2 are de-energized, which leaves the type wheel temporarily at rest.

The release of the wheel and its return to the normal position, in my wheel controlling means, is effected in the manner best explained as follows: 118 designates a second rock shaft that is formed with a notched flat face 18 that receives the front edge of the dot finger y , which finger, it should be stated, is the only finger that holds the wheel at the temporary rest position stated after the character is formed. The shaft 118, when rocked, acts as a cam to swing the finger y out from and release the type wheel, which operation is effected the same as is done in my printing telegraph mechanism disclosed in my co-pending application before referred to.

In Fig. 1, of my present application, 119 indicates the rod that extends up from the armature of the releasing magnet disclosed in my other application and which, when moved up in the direction indicated by the arrow, rocks the shaft 118, and thereby swings the finger y outwardly away from the said wheel.

It should be stated that when the wheel gets to the stop position before mentioned, the cam member 115, at the peripheral edge thereof, engages a lever (not shown) that actuates the switch devices for cutting out 130

the circuit that energizes the printing and releasing mechanism to thereby leave the type wheel free to be again advanced to a printing position.

5 From the foregoing description taken in connection with the accompanying drawing, the complete arrangement, the manner of its operation, and the advantages of my invention will be readily understood.

10 By reason of the utilization of a magnetic clutch device, that is under control of the operator at the transmitting end of the system, a simple, effective and positively acting means is provided for controlling the connection of the type or printing wheel with the actuating shaft.

15 An essential advantage in my improved structure is that at no time is there heavy work for the machine, the main line, the local battery or the motor, since the type wheel magnet pulls the type wheel into a clutched engagement with the rotating shaft only when it (the type wheel) is free to rotate with the shaft. Furthermore, in my present construction when the type wheel is held at rest, it being loosely mounted on the rotating shaft, though the latter is continuously revolving, there is practically no friction to overcome because the shaft magnet being normally not energized, produces no pull on the armature disk on the wheel, and in consequence has no effect whatever on the said wheel.

20 25 What I claim is:

30 35 1. In a printing telegraph of the character stated; a continuously rotatable shaft, an electromagnetic clutching element carried thereby, a type wheel loosely mounted on the shaft, means governed by the duration of a transmitted character impulse for energizing the said clutching element to couple the shaft and the type wheel together throughout the duration of the said impulse.

40 45 2. In a printing telegraph in which is included a continuously rotatable actuating shaft and a type wheel loosely mounted thereon; a magnetic clutch device that operates with the shaft and the wheel that couples the said wheel and shaft to cause the wheel to rotate with the shaft during each character transmitted electric impulse, and means controlled by said transmitted impulses for energizing the said magnetic clutch for the purposes stated.

50 55 3. In a printing telegraph in which is included a rotatable shaft and type wheel, electromechanical devices for holding the wheel to its predetermined positions during the operation of setting the wheel to a selected position; of means that coöperate with the wheel and the shaft that operates to clutch the wheel to the shaft under each transmitted character impulse that controls the setting of the wheel and the wheel se-

lecting devices, and which releases the said wheel when the said electric impulses cease.

4. In a printing telegraph, in which is included a rotatable shaft and a type wheel loosely mounted thereon, electromechanical devices including a stop finger for holding the wheel to predetermined positions during the operation of setting the wheel to a selected position; a magnetic clutch in which is included an armature member on the wheel, means for energizing the clutch set into action under each transmitted character impulse, said means including a source of electrical energy, a switch for opening and closing the source of energy, and connections that join the finger and the switch that controls the source of electrical energy for the magnetic clutch.

5. In a printing telegraph, a continuously rotating operating shaft, a type wheel mounted thereon, electromechanical devices for holding the wheel from turning, said devices being under control of and set into action during the time in which the transmitted impulses for building up the desired character are active, an electric magnet mounted on the shaft to turn therewith and which includes a disk on the type wheel that forms the armature, a source of local electrical energy for the magnet, a switch that controls the said source of energy, connections that join the switch with the electromechanical devices that effect the stoppage of the machine and adapted to be shifted as the said devices are energized and deenergized to shift the switch to energize or deenergize the electromagnet to couple or release the wheel and the shaft.

6. In a printing telegraph system of the character stated, a continuously rotative shaft, a printing wheel loosely mounted on the shaft, stop finger devices that engage and hold the wheel and are released from the wheel under electric impulses from the transmitting line, a magnetic clutch mounted upon and rotatable with the shaft and adapted when energized to clutch the printing wheel to turn with the shaft, a source of electrical energy for the clutch, a controlling switch for the said energy and connections that join the switch and the stop finger devices for shifting the said switch.

7. In a printing telegraph of the character stated, a continuously rotative shaft, an electromagnetic clutching element carried thereby, a type wheel loosely mounted upon the shaft, means governed by the duration of a transmitted character impulse for energizing the said clutching element to couple the shaft and the type wheel together throughout the duration of the last impulse and mechanism for effecting a further energization of the said magnetic clutching element upon the completion of the transmission of

a transmitted character for restoring the printing wheel to its initial position.

8. In a printing telegraph of the character stated, a continuously rotative shaft, an electromagnetic clutching element carried thereby, a type wheel loosely mounted upon the shaft, means governed by the duration of a transmitted character impulse for energizing the said clutching element to couple the 10 shaft and the type wheel together throughout the duration of the last impulse and mechanism for effecting a further energization of the said magnetic clutching element upon the completion of the transmission of 15 a transmitted character for restoring the printing wheel to its initial position, and devices controlled by the return movement of the printing wheel for cutting out the said further energization of the said magnetic clutching element.

9. In a printing telegraph in which is included a continuously rotative actuating shaft and a type wheel loosely mounted thereon, a stop finger for holding the wheel 25 from rotation, and means for moving the said stop finger to release the said wheel, an electromagnetic clutching element carried by the shaft, means governed by the duration of a transmitted impulse for energizing 30 the said clutching element to couple the

shaft and the type wheel throughout the duration of the said impulse, and mechanism actuated by the stop finger when moved to release the wheel for effecting a further energization of the said magnetic clutching 35 element upon the completion of the transmission of a transmitted character to restore the said wheel to its initial position.

10. In a printing telegraph system of the character stated, a continuously rotative 40 shaft, a printing wheel loosely mounted upon the said shaft, a stop finger device that engages and holds the wheel from rotation, and is released from the wheel under electric impulse from the transmitting line, 45 a magnetic clutch mounted upon and rotatable with the shaft and adapted when energized to clutch the printing wheel to turn with the shaft, a source of electric energy for the said magnetic clutch, a controlling 50 switch for the said energy, connections that join the switch and the stop finger devices for shifting the said switch, and means operable under transmitted impulses for shifting said finger devices.

OSCAR L. KLEBER.
